GRINDING MACHINE ABRASIVE ELEMENT

Joseph Sunnen, Kirkwood, Mo.

Application October 29, 1932. Serial No. 640,272

9 Claims. (Cl. 51—184.1)

My invention has relation to improvements in grinding or abrading elements for grinding or honing machines of the type illustrated and described in my co-pending application, Serial No. 5 233,788, filed November 17, 1927, and it consists in the novel features of construction more fully set forth in the specification and pointed out in the claims.

The principal object of the present invention 10 is to provide a grinding element for a grinding machine of the type described in the above referred to application, the abrasive stick of which is so constructed that practically the entire stick may be used, thus prolonging the life of the 15 abrasive elements. This advantage, as well as others inherent in the invention, will be better apparent from a detailed description thereof in connection with the accompanying drawing, in which:

20 Figure 1 is a side elevation of a grinding machine equipped with my improved grinding elements and parts of the carrier for said elements being broken away; Fig. 2 is a horizontal cross-section taken on the line 2—2 of Fig. 1; Fig. 3 is 25 a face view of my improved grinding element; Fig. 4 is a side elevation thereof; and Fig. 5 is a cross-sectional detail taken on the line 5—5 of Fig. 3.

Grinding machines of the type described in said 30 application are well known in the art and as shown in the drawing comprise a holder 1 supported from a shaft 2 by a universal joint including the fork 3, collar 4 and studs 5, 5. The holder 1 is provided with a longitudinally disposed axial bore 35 6 in which is mounted an elongated pinion 7 which cooperatively engages a pair of rack bars 8, 8 carrying on their outer ends a grinding element 9. As described in the aforesaid application, there are two such grinding elements 9, 9 and also two guide elements 10, 10 likewise carried 40 on the outer ends of rack bars 11, 11. The rack bars 8, 8 for the grinding elements are slidably mounted in transverse bores 12, 12, and the rack bars 11, 11 for the guide elements are slidably 45 mounted in transverse bores 13, 13 disposed at right angles to the bores 12, 12 (Fig. 2). The constructional details just described are common to grinders of this type and of themselves form no part of the present invention which is restricted to the construction of the grinding elements per se illustrated in Figs. 3 to 5 inclusive.

The grinding elements as heretofore constructed 50 comprise a channel-shaped holder for the abrasive stone or stick, and when the stone has been

worn down to a thickness so that it is flush with the top edges of the sides of the channel it is no longer serviceable as the channel sides will then encounter the wall of the cylinder being ground. When these stones have been worn to this extent 60 there is still a good deal of serviceable material in the stone which cannot be used because of the said obstruction caused by the sides of the channel. Mechanics in some instances refill these channels by inserting new abrasive stones therein 65 but such refilled elements are often unsatisfactory because of the inferiority of the abrasive used.

It is the object of the present invention to provide a grinding element comprising an abrasive stone and holder therefor, said holder being 70 so constructed as to allow practically the entire stone to be used in grinding operations, thereby overcoming the waste inherent in the old construction as above described.

Referring now to Figs. 3 to 5 inclusive, 14 represents the holder for the stone 15, said holder comprising a base 16 and a fluted side wall 17 disposed on the following side of the holder with respect to the direction of rotation thereof when 75 the grinder is in action. It will be noted that the adjacent flutes 18, 18' extending along the length of the wall 17 are oppositely disposed, that is, flutes 18 being open outwardly while the flutes 18' open inwardly, said flutes having connecting walls 19 in common between which extend the walls 20, 20'. The walls 20, 20' are perpendicular to the inclined supporting surface 22 of the holder 14, and the stone 15 is disposed on said surface 22 in abutting relation with the 80 walls 20 of the flutes 18. The abrasive stone 15 is caused to adhere to the surface 22 and outer surfaces of walls 20 by means of a cement grouting which is applied to said surface 22 and walls 20 and allowed to flow into the flutes 18', 85 thereby causing adhesion between the stone and the inner surfaces of wall 20' so that the stone is firmly cemented in place in the holder 14. By imparting to the backing 17 the fluted or corrugated shape as shown the necessary strength is 90 obtained for backing up the stone 15 in its grinding operations with a minimum amount of metal. In fact, if the same amount of strength were to be imparted to a plain wall of uniform thickness considerably more cross-sectional area would be 95 required. The advantage of the reduction in the amount of metal will be readily apparent when it is considered that I propose that the backing 17 shall be worn down together with the abrasive stone 15 after the latter has been reduced in 100 110

thickness so that its abrading surface α shall lie in the same plane as the free edge of the backing 17 (as shown by the dotted line in Fig. 5).

5 In order that the backing may be worn off by contact with the cylinder wall after the grinding stones 15 have been reduced, as above described, and at the same time will not score the cylinder wall or interfere in any manner with the grinding thereof, I form the entire holder 14 of a metal 10 that is softer in the scale of hardness than the cast iron of the cylinder and they will at the same time be pulverized by contact with the cylinder without spreading or smearing over the cylinder wall. In other words, the metal of which the holder 14 is composed, and preferably the backing 17, should be friable and wear by attrition in contact with the cylinder wall without scoring said wall or filling the pores thereof. I have found that die cast metal containing the proper proportions of zinc, aluminum and copper will serve the purpose, although I do not wish to be restricted to this particular metal as I desire to avail myself of any metal or alloy 25 that has the properties herein specified. A specific composition of metal that serves the purpose well is one containing 93% zinc, 5% aluminum and 2% copper.

It will be observed that the inclination of the 30 surface 22 tilts the stone 15 slightly forwardly with respect to the direction of the rotation of the grinder (Fig. 2). This avoids the necessity for shaping the surface α of the stone 15 to adapt the same to have a wide contact with the surface 35 of the cylinder, which would otherwise be necessary owing to the fact that the racks 8, 8 are to one side of the rotation axis of the machine. The inclination of the surface 22 is just sufficient so that said surface may be perpendicular to a 40 radial line α drawn from the rotation axis of the machine through the center of the stone (Fig. 2).

The holder 14 may be carried on the ends of the racks 8, 8 in any desirable manner although I prefer that the extremities 8' of the racks be 45 reduced in diameter and passed through counter-sunk openings o, o in the base 16 of the holder after which the end of each reduced extremity 8' is upset into the countersunk portion of the opening to produce a substantial riveted connection.

50 Having described my invention, I claim:

1. An abrasive element for cylinder grinding machines comprising supporting members, a holder carried thereby, and a stone fixed in said holder, said holder having a suitable backing for the stone, and said backing consisting of a metallic alloy having a zinc base and containing aluminum and copper.

2. An abrasive element for cylinder grinding machines comprising supporting members, a metallic holder carried thereby, and an abrasive stone fixed in said holder, said holder having an abutment wall adjacent to one side of the stone, the metal of said abutment wall being of sufficient softness to wear without abrading the cylinder.

3. An abrasive element for cylinder grinding machines comprising supporting members, a holder carried thereby, and a stone fixed in said holder, said holder having a suitable backing for the stone, said backing comprising a series of juxtaposed ribs extending from end to end of the stone.

4. An abrasive element for cylinder grinding machines comprising supporting members, a holder carried thereby, and a stone fixed in said holder, said holder having a suitable backing for the stone, said backing comprising a series of juxtaposed ribs formed integrally with the holder.

5. An abrasive element for cylinder grinding machines comprising supporting members, a holder carried thereby, and an abrasive stone fixed in the holder, said holder comprising a base member and a fluted abutment member contiguous to one side of the base member, said stone being cemented to the base member and abutment member.

6. An abrasive element for cylinder grinding machines comprising supporting members, a holder carried thereby, and an abrasive stone fixed in the holder, said holder comprising a base member and an abutment member contiguous to one side of the base member, said abutment member having a series of pockets formed on its inner surface, and a cement grouting between the stone and the base and the backing, said grouting extending into the pockets aforesaid.

7. An abrasive element for cylinder grinding machines comprising supporting members, a holder carried thereby, and a stone fixed in said holder, said holder having a suitable backing for the stone, said backing comprising a fluted wall.

8. An abrasive element for cylinder grinding machines comprising supporting members, a metallic holder carried thereby, and an abrasive stone fixed in said holder, said holder having a corrugated abutment wall adjacent to one side of the stone.

9. An abrasive element for cylinder grinding machines comprising supporting members, a holder carried thereby, and a stone cemented in said holder, said holder consisting of a metallic alloy containing zinc and aluminum.
